HUMIDIFYING RADIATOR

Andrew U. Jones, Montreal, Quebec, Canada

Application March 25, 1932, Serial No. 601,180

9 Claims. (Cl. 257—180)

This invention relates to humidifying radiators and the object is to provide simple and inexpensive means for substantially increasing the water evaporating area and efficiency of the radiator sections used for humidifying purposes.

The essential feature consists in arranging a covering of absorbent material in contact with the outer surfaces of a hollow heat radiating section and supplying water to said material in sufficient quantity to maintain a high rate of evaporation. The water to be evaporated is thus evenly distributed over a relatively large evaporating area afforded by the heated outer surface of the radiator section and is maintained at approximately the same temperature as the circulating medium flowing through the section so that heat losses, due to evaporation, are reduced to a minimum. By using a covering material of proper thickness and maintaining it saturated with water in excess of its evaporating capacity excessive accumulation of salt tending to reduce the water absorbing capacity of the covering material is prevented by reason of the fact that most of the salt is carried away by the surplus water as it drips from the covering material. Each radiator section to which the absorbent covering material is applied preferably has its top wall formed to provide a water containing recess into which portions of the covering material are extended to provide for the distribution of water from the recesses over the outer surfaces of the section with which the covering material is in contact. This preferred arrangement is not, however, absolutely essential since other methods may be employed for supplying water to the absorbent coverings of the various sections.

Proceeding now to a more detailed discussion of the invention reference will be had to the accompanying drawings wherein—

Fig. 1 is a side elevation of a humidifying radiator constructed in accordance with this invention.

Fig. 2 is a vertical transverse sectional view taken along the line 2—2 of Fig. 1.

Fig. 3 is a transverse sectional view of one of the radiator sections showing the manner of attaching the absorbent covering material thereto.

Fig. 4 is a vertical sectional view of a modified type of humidifying radiator provided in accordance with this invention.

Fig. 5 is a view similar to Fig. 4 showing a further modification.

The humidifying radiator shown in Figs. 1 and 2 comprises a series of vertically spaced hollow radiator sections A coupled together by conventional coupling nipples (not shown) engaged in the nipple receiving bosses B. Each section A is preferably offset with respect to the next lower section to produce the horizontally staggered arrangement illustrated in Fig. 2. The top wall 55 of each section is recessed to provide a water tray

C bounded by upwardly projecting side walls D and end walls E forming continuations of the side and end walls of the body portion of the section. The bottom wall F of each section is made substantially V-shaped in cross section so that its lowest point which coincides with the apex of the V is substantially centered between the sides of the section. 65

The tray C of each section is supplied with a suitable quantity of water which is evenly distributed over the outer side and bottom surfaces of the section by means of a covering G of highly absorbent material arranged in contact with said bottom and side surfaces and having marginal portions G¹ entering the tray to draw water 70 therefrom by capillary attraction. The covering G may be made of any absorbent material suitable for the purpose for which it is intended and may be secured in place in various ways. It is preferred, however, to make the covering of 75 highly absorbent textile material of such thickness that the covering becomes saturated with water in excess of its evaporating capacity so that a considerable quantity of surplus water is continuously dripping from the lowest point of 80 each covering into the tray C of the next lower section. This saturation of each covering to produce a copious dripping of water from its lowest point is of advantage in that it tends to diminish accumulation of salt in the pores of the 85 covering and ensures an adequate supply of water to each of the trays C by reason of such dripping, with the exception of the uppermost tray C to which the water to be evaporated is initially supplied through a tap or faucet H. 90

As herein shown each covering G comprises a body of highly absorbent textile material made in the form of a long and relatively narrow tube into which a pair of lengthwise extending retaining rods J are inserted. The intermediate portion of the tube is then flattened against the bottom and side surfaces of the section A with the sleeve-like marginal portions G¹ dipping into the tray C and held against the inner sides of the tray walls D by means of the inserted retaining rods J. This flattening of the tube provides a two-ply covering including the inner and outer plies appearing at G² and G³ in Fig. 4. The weight of the rods J will ordinarily be sufficient to hold the covering in place, but additional securing means may be provided at each end of the covering in the form of a strip K of copper or other ductile material bent to extend across the bottom and upwardly along the sides of the covering and having its extremities bent inwardly over the rod 100 containing portions of the covering as indicated at K¹. 105

When the radiator is in operation the water contained in the tray C of each section, with the exception of the lowermost section, is distributed 110

- by the covering G over the heated bottom and side surfaces of the section so that these surfaces, as well as the top surface, are used for evaporating purposes. Each covering G also serves as the 5 medium for transferring water from each tray to the next lower tray since it absorbs water in excess of its evaporating capacity and provides a sufficient drippage of surplus water to ensure an adequate supply for each tray. The water to 10 be evaporated is initially supplied to the tray C of the uppermost section through the tap or faucet H and is conducted from this tray to the remaining trays by means of the coverings G, as previously explained.
- 15 In order to prevent drippage of water on the floor, the lowermost section A is left uncovered and has its tray C connected to a drain pipe L which carries away the water dripping into said tray from the covering of the next upper section.
- 20 In some instances it may not be desirable to depend on the drippage from each covering G as the sole means of transferring water from each tray C to the next lower tray. In such cases each section A may have its tray provided 25 with any suitable form of outlet M through which a portion of the water supplied to the tray is gradually drained into the tray of the next lower section.
- It may also be pointed out here that the use 30 of the coverings G is not limited to humidifying radiator sections of the particular type described herein since these coverings may be used to equal advantage with humidifying sections of the water course type disclosed in my co-pending applications Serial Nos. 593,123 filed Feb. 15, 1932 and 601,179 filed March 25, 1932, which have now matured into Patent No. 1,876,142 granted Sept. 6, 1932 and Patent No. 1,886,192 granted Nov. 1, 1932, respectively.
- 40 The coverings G may also be used in connection with ordinary horizontal radiator sections as suggested in Fig. 4. In this case the central member P of each section is completely surrounded by a covering R of highly absorbent 45 material. A water containing tray S is mounted directly above the uppermost member P and has its bottom and side surfaces covered by a sheet of absorbent material T, the lateral margins of which are dipped into the tray as indicated at 50 T¹ to draw water therefrom by capillary attraction. This covering T is retained in place on the tray by means of the retaining bands U which are substantially similar to the retaining bands K previously described herein. With this arrangement the covering R of each member P is 55 maintained saturated by drippage from the covering of the next upper member P, the covering of said uppermost member P being maintained saturated by drippage from the covering T of the 60 tray. The drippage from the lowermost covering is caught in a tray V which is provided with a drain pipe W.
- In Fig. 5, I have suggested another modification in which the tray S is replaced by one of the cover heat radiating sections A described in 65 connection with Figs. 1 to 3 inclusive.
- Having thus described my invention, what I claim is:—
- 70 1. A hollow radiator section having its top wall shaped to provide a water containing recess and having its bottom and side surfaces covered by absorbent material entering said recess to draw water therefrom by capillary attraction.
- 75 2. A radiator section having its top wall shaped to provide a water containing tray, a body of absorbent material covering the outer side and bottom surfaces of the sections and having opposite marginal portions thereof dipped into said tray, and retaining rods associated with said marginal portions for holding the covering in place. 80
3. A hollow radiator section having its top wall shaped to provide a water containing tray, a removable covering of absorbent material overlying the bottom and side surfaces of the section and having side portions thereof dipped into said tray and means for removably securing the covering in place on said section. 85
4. A radiator section as claimed in claim 2 including retaining strips extending across the bottom and upwardly along the sides of the covering and having their ends bent inwardly to overlie said rods. 90
5. A hollow radiator presenting a series of vertically spaced radiator sections, each having a top recess and a body of absorbent material covering its side and bottom surfaces, said covering having portions thereof entering the recess to draw water therefrom by capillary attraction, 100 and means for supplying water to the top recess of the uppermost section. 105
6. Humidifying apparatus comprising a hollow heat radiating member having an outer covering of absorbent material and an internal passage for the circulation of a heating medium therethrough a body of absorbent material arranged directly above said member, and means for saturating said body with water to maintain a drippage of surplus water into the covering of 110 said member. 115
7. Humidifying apparatus comprising a hollow heat radiating member having an outer covering of absorbent material and an internal passage for the circulation of a heating medium there- 120 through, a water containing tray mounted above the member in a position overlying said covering, and means for transferring water from the tray to said covering comprising a body of absorbent material arranged to draw water from the tray by capillary attraction, said body being positioned so that the water dripping therefrom is delivered to said covering. 125
8. Humidifying apparatus comprising a radiator presenting a series of vertically spaced heat radiating sections provided with internal passages for the circulation of a heating medium therethrough, each section having an outer covering of absorbent material, and means for supplying water to the covering of the uppermost section so that each covering, with the exception of the uppermost covering, is saturated by surplus water dripping from the next upper covering. 130
9. Apparatus for heating and humidifying the air of a room or other enclosure comprising a radiator presenting hollow heat radiating sections, means for circulating a heating agent through said radiator to heat the surrounding air, a closely fitting wrapping of absorbent material applied to and completely surrounding one or more of said sections, and means for continuously adding water to said wrapping or wrappings to maintain the same in a saturated condition whereby the humidity of the air surrounding the radiator is increased in substantial 140 degree by evaporation of the water in contact with the heated outer surface of said sections. 145
